UNITED STATES PATENT OFFICE.

JAMES F. BOHAN AND CORNELIUS J. HARTMAN, OF SCRANTON, PENNSYLVANIA.

GUARD FOR TEXTILE MACHINERY.

1,249,889.

Specification of Letters Patent. Patented Dec. 11, 1917.

Application filed May 14, 1917. Serial No. 168,409.

To all whom it may concern:

Be it known that we, JAMES F. BOHAN and CORNELIUS J. HARTMAN, citizens of the United States, residing at Scranton, in the 5 county of Lackawanna and State of Pennsylvania, have invented certain new and useful Improvements in Guards for Textile Machinery, of which the following is a specification.

- 10 This invention relates to a guard for textile machinery, and we have shown the same applied to what is known as the 5-B twisting and doubling machine made by the Atwood Machine Company, showing only so 15 much thereof as will illustrate the position occupied by and the use of the guard. It will of course be understood that a large number of the guards are employed on each complete machine.
- 20 The object of the guard or shield is to prevent the silk from winding around the driving shaft. A special advantage of the guard as used by us is that it can be put on without tools or employing any fastening devices, and can be lifted off readily to get at the gears.

In the accompanying drawings,

Figure 1 is a side elevation showing a portion of the machine, the saddle, saddle 30 bracket and rollers, with the guard in position.

Fig. 2 is a front view.

Fig. 3 is a section on the line 3—3 of Fig. 1, the saddle being removed.

35 Fig. 4 is a perspective view of one of the guards, detached.

In the drawing 1 designates the saddle, 2 the saddle bracket, 3 the rollers and 4 the gears, carried by the saddle and supported 40 with the saddle on the bracket, and 5 are uprights carried by the bracket. The driving roller 6 is provided with a gear 7 which meshes with the gears 4. 8 is the rod supporting the bracket and 9 the spring that 45 disengages the gears 4 from the gear 7 on the breaking of a thread.

Our guard consists of a plate 10 which is pressed outwardly at 11 thereby forming on the inner face of the guard a longitudinally extending channel adapted to receive the gear 7.

At its upper end the plate 10 is bent to form an integral, horizontal flange 12. The central portion of the flange lies in the horizontal plane of the upper edge of the body.

portion of the plate 10 while the marginal portions 13 and 13^a are offset or elevated forming side ribs. The flange 12 is transversely cut as at 14 forming a slot that registers with the upper end of the channel 60 11 and through which the gears 4 and gear 7 mesh. The ribs are slotted as at 15 to fit over the uprights 5 of the bracket. The course of the thread is indicated at 16.

It will be noted that the guard at the sides 65 extends beyond the bracket.

To put the guard on it is only necessary to lift up the saddle, thereby removing the rollers 3, and slip the guard into place the slots 15 receiving the uprights 5, and it is 70 held in place by the uprights and by the saddle.

To lift off the operation is practically as simple, the saddle being lifted off and then the shield simply slipped over the uprights 75 giving immediate access to the gear 7 and the drive shaft. The guards are made of tin, and are cheap, durable and a boy can put them in place.

What we claim is:

1. In a device of the kind described, the combination with a saddle and saddle bracket, the latter having uprights, of a guard adapted to rest beneath the saddle, said guard comprising a flange held between the saddle and the bracket and slotted to fit over said uprights. 80

2. In combination with a twisting and doubling machine having a drive roller, a gear thereon, a saddle bracket having uprights, a saddle, and rollers and gears carried by the saddle, of a flanged guard, the flange being slotted to permit meshing of the gears, and slotted to fit over said uprights, said flange when in position resting 90 between the bracket and the saddle, and held in place by said uprights. 95

3. A guard of the kind described comprising a plate having a longitudinal gear receiving channel formed on its inner face 100 and flanged at one end, said flange having slotted elevated side marginal ribs, and the flange being slotted in alinement with the channel of the plate first mentioned, as and for the purpose set forth. 105

In testimony whereof we affix our signatures.

JAMES F. BOHAN.
CORNELIUS J. HARTMAN.
